UNITED STATES PATENT OFFICE.

CARLO CAVALLI, OF TURIN, ITALY, ASSIGNOR TO F. I. A. T., A CORPORATION OF NEW YORK.

DESIGN FOR AN AUTOMOBILE RADIATOR AND HOOD.

48,219.

Specification for Design.

Patented Nov. 30, 1915.

Application filed May 29, 1915. Serial No. 31,301. Term of patent 14 years.

To all whom it may concern:

Be it known that I, CARLO CAVALLI, a subject of the King of Italy, residing at Turin, Province of Piedmont, Italy, have invented a new, original, and ornamental Design for an Automobile Radiator and Hood, of which the following is a specification, reference being had to the accompanying drawing, forming part thereof.

Figure 1 is a front elevation of an auto-

mobile radiator and hood, showing my new design, and Fig. 2 is a side elevation.

I claim:

The ornamental design for an automobile radiator and hood, as shown.

CARLO CAVALLI.
